FISH LURE

Serge Krivicky, 920 Wilder Ave., Montreal,
Quebec, Canada

Filed Feb. 11, 1963, Ser. No. 73,511

Term of patent 14 years

(Cl. D31—4)

FIG. 1

FIG. 2

FIG. 3

FIG. 4

FIG. 5

FIG. 1 is a front elevation of one side of a fish lure embodying my new design,

FIG. 2 is a view of an end thereof,

FIG. 3 is a front elevation of the other side thereof,

FIG. 4 is a top view, and

FIG. 5 is a bottom view.

I claim:

The ornamental design for a fish lure, substantially as shown.
